UNITED STATES PATENT OFFICE

WILLIAM LINDSAY, OF CHICAGO, ILLINOIS, ASSIGNOR TO ECONOMY FUSE AND MANUFACTURING COMPANY, OF CHICAGO, ILLINOIS, A CORPORATION OF NEW YORK

SWITCH MECHANISM

Application filed December 16, 1927. Serial No. 240,414.

The present invention relates to improvements in switch mechanism. The present invention is illustrated and will be described in connection with a type of switch which is frequently operated, such for example, as an electric light switch. The invention is illustrated in connection with a switch of the pull chain type, though it will be understood as the description proceeds that the invention is of much broader application.

An object of the present invention is to provide a switch contact which may be made and assembled at small expense and which is well adapted to stand up under frequent circuit making and circuit breaking operations.

A further object is to provide a switch contact of simple construction providing an efficient current carrying portion operative under normal current carrying conditions and providing a portion operative under circuit making and circuit breaking conditions to minimize sparking and pitting.

A further object is to provide an electric switch of improved construction involving a resiliently urged movable contact member and a relatively stationary contact member cooperating therewith, which relatively stationary contact member has a resilient portion adapted to cooperate effectively under normal current carrying conditions with said resiliently urged contact member and which has a second resilient portion adapted to cooperate effectively with said resiliently urged member under circuit making and circuit breaking conditions.

A further object is to provide an electric switch well adapted to quantity production, which may be assembled at a minimum of expense.

Further objects will appear as the description proceeds.

Referring to the drawings—

Figure 1 is a view in elevation of an electric switch embodying the principles of the present invention;

Figure 2 is a top plan view of the structure shown in Figure 1;

Figure 3 is a sectional view taken along the

plane indicated by the arrows 3—3 of Figure 2;

Figure 4 is a perspective view, on an enlarged scale, of a contact member involved in the structure shown in Figures 1, 2 and 3; and

Figure 5 is a blank from which the contact member shown in Figure 4 may be swaged.

The numeral 10 indicates a disk which should be of insulating material. Said disk 10 has a standard or post 11 secured thereto, which post 11 provides a slidable support for a relatively movable contact member 12. Said contact member 12 is selectively urged toward either of the two ends of the post 11 by means of the spring 13, which spring 13 has an extremity 14 extending through an aperture 15 in said member 12. The post 11 is provided with the slot 16, having closed ends, which closed ends limit movement of the extremity 14 of the spring 13, and therefore limit longitudinal movement of the contact member 12. Said spring 13 is mounted upon the arm 17, which arm is controlled by ratchet mechanism, indicated as a whole by the numeral 18. The ratchet mechanism and the means associated therewith for biasing the contact member 12 selectively to its two extreme positions do not constitute the subject matter of the present invention and need not be described in detail herein, inasmuch as any preferred means known to those skilled in the art may be utilized to operate the member 12 into and out of the position shown in Figure 1. At present it is preferred to use the structure disclosed in applicant's Patent No. 1,706,793, granted March 26, 1929.

The relatively movable contact member 12 is provided with the pair of side walls 19 having the flanges 20—20. Said relatively movable contact member 12 is adapted to have bridging relationship with a pair of relatively stationary contacts 21—21, which relatively stationary contacts 21—21 are preferably identical with each other. As shown in Figure 4, each contact 21 may consist of sheet metal having a base portion 22 provided with the aperture 23. Figure 5 shows a blank from which the contact 21 may be swaged, said blank having cut out portions on two op-

posite sides as indicated by the numerals 24—24. Longitudinal slits 25 communicate with said cut out portions 24—24 and extend in the direction of the aperture 23. Said slits 25 provide the neck 26, the fingers 26A and the head portion 27. As indicated in Figures 3 and 4, the neck 26 is bent downwardly from the base portion 22 and is bent upwardly intermediate of its length, as indicated by the numeral 28. The neck 26, therefore, provides an abutment for a purpose which will be referred to hereinafter. The head 27 is bent along a transverse axis to provide a contact engaging portion 29. The extremity of the head 27 is flared rearwardly from the portion 29, as indicated by the numeral 30. The fingers 26A—26A are swedged upwardly intermediate of their length transversely of the member 21 to provide contact making portions 26B—26B adapted to cooperate with the lower flanges 20—20 of the movable contact member 12. The downwardly extending portion of the neck 26 of each contact member 12 is disposed within a corresponding aperture 31 in the disk 10. Said members 21—21 are anchored in position, preferably by means of the center and side contacts of the electric switch in the event that the switch is used in an electric socket or the like. To the right of the vertical center line in Figure 3, the contact member 21 is anchored in position by the center contact 32, which, it will be noted, has an extremity 33 extending through the aperture 34 in the disk 10 and through the aperture 23 in the corresponding member 21, and swedged over upon the upper side of the corresponding contact member 21. The left-hand contact member 21, as the parts are viewed in Figures 2 and 3, is anchored in place by means of the side terminal 35, which has an extremity 36 extending through the aperture 23 in the corresponding contact member 21 and through the aperture 37 in the disk 10, said extremity 36 being riveted over on the under side of said disk 10. If preferred, the contact 21 may be further anchored by means of prick punches indicated by numerals 38—38, which prick punches are located at the side edges of said member 21.

By reason of the upwardly swedged portions 26B of the contacts 21—21, said contacts 21—21 will not lie flat upon the disk 10 when anchored in position but will have an upward spring intermediate of the length of the fingers 26A—26A. By reason of this fact, the resiliently urged contact member 12 will have a slight rubbing action upon the upwardly swedged portions 26B—26B of the fingers 26A—26A when said contact member 12 is moved into and out of circuit making relationship with the contacts 21—21. By reason of this fact the contact member 12 will have a cleaning action and good contact 35 will be had between the contact member 12

and the contacts 21—21 during the normal operation of the switch of which said members form a part. When the contact member 12 is in circuit making position it is disposed between the portions 29—29 of the head portions 27—27 of the contacts 21—21. Said head portions 27—27 by reason of the resiliency of the metal of the members 21—21, are yieldingly held against the walls 19—19 of the contact member 12. When said contact member 12 is being moved out of circuit making relationship with the contacts 21—21, and when said contact member 12 is being moved toward contact making relationship with the contacts 21—21, the final breaking and the initial making of circuit making relationship will be with a snap action whereby sparking and pitting will be reduced to a minimum.

It will be clear that the outwardly extending portion of the neck 26 of each contact 21 provides a ready means for locating the contacts 21—21 relative to the apertures 37 in the disk 10. It will also be clear that the contact members shown and described cooperate effectively with the usual center and side contacts of an electric lamp socket or the like whereby the matter of assembly is simplified.

Though a preferred embodiment of the present invention has been described in detail, many modifications will occur to those skilled in the art. It is intended to cover all such modifications as fall within the scope of the appended claims.

What is claimed is—

1. In a switch, in combination, a supporting member, a pair of relatively stationary contacts carried by said supporting member, a movable contact adapted to have bridging relationship with said relatively stationary contacts, each of said stationary contacts comprising a base portion having an upwardly biased part intermediate of its length, a neck portion having interfitting relationship with said supporting member and a head portion carried by said neck portion disposed above said base portion intermediate of the length of said base portion, the head portions of said relatively stationary contacts being positioned to embrace said relatively movable contact.

2. In a switch, in combination, a supporting member, a pair of relatively stationary contacts carried thereby, a relatively movable contact adapted to have bridging relationship with said relatively stationary contacts, each of said relatively stationary contacts having a base portion disposed upon said supporting member and biased away from said supporting member intermediate of its length, a neck portion disposed in angular relationship with said base portion, and a head portion carried by said neck portion,

said relatively movable contact having walls adapted to engage said head portions and another wall portion adapted to engage said base portion.

5. 3. In a switch, in combination, a supporting member, a pair of relatively stationary contacts carried thereby, a relatively movable contact adapted to have bridging relationship with said relatively stationary contacts,
 10 each of said relatively stationary contacts comprising a base portion sprung up from said supporting member intermediate the length of said base portion and a head portion, said relatively movable contact having
 15 side walls disposed, when said relatively movable contact is in bridging relationship with said relatively stationary contacts, between said head portions and having another wall portion adapted to engage said upwardly sprung base portion.

4. In a switch, in combination, a relatively stationary contact, a relatively movable contact, a supporting member for said relatively stationary contact, said relatively stationary contact having a base portion upwardly swedged intermediate of its length and a head portion extending upwardly from said base portion, said relatively movable contact having a pair of walls in angular relationship
 25 with one another, one of said walls being adapted to be positioned against said base portion, the other of said walls being adapted to have wiping relationship with said head portion.

30 5. A contact member comprising a base having a pair of substantially parallel fingers, a neck secured to said base and disposed between said fingers, said neck being disposed in angular relationship to said base and having a head at its extremity.

35 6. A contact member comprising a base having a pair of substantially parallel fingers, a neck secured to said base and disposed between said fingers, said neck being disposed in angular relationship to said base and having a head at its extremity, said head being angularly bent transversely of said fingers.

40 7. A contact member comprising a base having a pair of substantially parallel fingers, a neck secured to said base and disposed between said fingers, said neck being disposed in angular relationship to said base and having a head at its extremity, said fingers being bent transversely thereof to give said fingers an upward spring intermediate of their length.

45 8. A contact member comprising a base having a pair of substantially parallel fingers, a neck secured to said base and disposed between said fingers, said neck being disposed in angular relationship to said base and having a head at its extremity, said fingers being bent transversely thereof to give said fingers an upward spring intermediate

of their length, said head being bent in a direction transversely of said fingers.

Signed at Chicago, Illinois, this 13th day of December, 1927.
